CLAIM

The ornamental design for an orifice for an aerosol bottle for dispensing a foam hair care composition, as shown and described.

DESCRIPTION

FIG. 1 is a perspective view of an orifice for an aerosol bottle for a foam hair care composition, embodying our new design;

FIG. 1 is a front view thereof;

FIG. 3 is a first side view thereof;

FIG. 4 is a back view thereof;

FIG. 5 is a second side view thereof;

FIG. 6 is a top view thereof; and,

FIG. 7 is a bottom view thereof.

The broken lines depict the portions of the aerosol bottle for dispensing foam hair care composition that form no part of the claimed design.
